UNITED STATES PATENT OFFICE.

WILLIAM H. WALSH, OF NEW YORK, N. Y.

DESIGN FOR A BADGE.

SPECIFICATION forming part of Design No. 23,831, dated December 4, 1894.

Application filed October 25, 1894. Serial No. 526,982. Term of patent 14 years.

To all whom it may concern:

Be it known that I, WILLIAM H. WALSH, of New York city, in the county and State of New York, have invented and produced a new 5 and original Design for a Badge, of which the following is a specification.

Reference is to be had to the accompanying drawing, forming a part of this specification, in which the figure is a face view of a badge 10 embodying my design.

The leading feature of my design consists in a Maltese cross A, surrounded by a circular band B, and containing at its middle the configuration of a heart C.

Minor features of my design are the border 15 A', for the Maltese cross A and the circular borders B' or B², for the band. The heart C is ornamented by the representation of a chain C', extending across the heart and the representation of a flame C² at the top. 20

I claim—

The design for a badge as herein shown and described.

WILLIAM H. WALSH.
